ORNAMENTAL NECKTIE CLASP

Irving F. Chichester, Rochester, N. Y., assignor
to Hickok Manufacturing Co. Inc., Rochester,
N. Y., a corporation of New York

Application January 27, 1949, Serial No. 73,193

1 Claim. (Cl. 40—140)

1

This invention relates to improvements in jewelry and has reference especially to a novel construction of necktie clasp.

One object of the invention is to provide an improved necktie clasp of simple, efficient, inexpensive construction having a front portion that will enable the ready selective association and securing of character elements thereon so that the same will be displayed to present a pleasing ornamental appearance.

The invention comprehends a necktie clasp having a relatively long, slender, tubular front member of relatively light construction adapted to receive therein attaching portions of character elements or members to support the same in upright position thereon and a particularly important novel feature of the invention resides in the special construction of the tubular character holder member and its connection with a rear clamping member, whereby the tubular character holder member is reinforced by the connecting means, and a simple, strong, efficient clasp is provided that can be produced at low cost.

The invention, with other objects and advantages thereof, and the particular construction, combination and arrangement of parts comprising the same will be understood from the following detailed description when considered in connection with the accompanying drawings forming part hereof and illustrating two embodiments of the invention.

In the drawings:

Fig. 1 is a front elevation of a necktie clasp constructed in accordance with the present invention;

Fig. 2 is a top plan view of the same;

Fig. 3 is a vertical longitudinal section on the line 3—3 of Fig. 2;

Fig. 4 is a horizontal section on the line 4—4 of Fig. 1;

Fig. 5 is a transverse section to an enlarged scale on the line 5—5 of Fig. 3;

Fig. 6 is a transverse section on the line 6—6 of Fig. 2;

Figs. 7 and 8 are respectively a detail rear perspective and top plan view of one of the character elements;

Fig. 9 is a transverse section of the character element shown in Fig. 7;

2

Fig. 10 is a transverse section of a slightly modified form of the tubular front member with a slightly modified form of character element mounted thereon;

5 Fig. 11 is a front elevation of a modified form of the device;

Fig. 12 is a top plan view of the construction shown in Fig. 11;

10 Fig. 13 is a horizontal section on the line 13—13 of Fig. 11;

Fig. 14 is a transverse section on the line 14—14 of Fig. 11;

15 Figs. 15 and 16 are respectively a detail side elevation and end elevation of one of the character elements of the construction shown in Fig. 11.

While two embodiments of the invention are illustrated in the drawings, it will be understood that minor changes and modifications may be 20 made in the particular constructions shown and the invention may be embodied in other forms as will appeal to those skilled in the art and falling within the scope of the appended claims without departing from the spirit of the invention.

25 Referring to a detailed description of the particular embodiment of the invention illustrated in Figs. 1 to 8 of the drawings, the construction shown comprises a relatively long, slender, flat front bar 17 having a reverting end portion 18

30 to the end of which is pivotally connected, intermediate its ends, a spring-pressed clamping member 19. In accordance with the present invention, a tubular member 20 is secured on the front bar 17 at the front side thereof, said tubular member being adapted to support thereon a plurality of character elements 21. The tubular character holder member 20 is of substantially the same length and width as the front bar 17 and conceals the same from view from the front side thereof.

35 In this particular embodiment of the invention, the tubular front member 20 is substantially half-round or of general semi-circular shape in cross section, the same having a curved front wall 22 and a flat back wall 23, the latter fitting against the front face of the front bar 17 and being soldered or otherwise suitably secured thereon.

The tubular character holder member 20 is provided in the upper side of its curved front wall

wall 23, the slot extending throughout the full length of the tubular member. The tubular member is made from relatively light metal tubing of general semi-circular cross sectional form, the longitudinal slot 24 being milled in the curved wall 22. At each end, the tubular member 20 has a tab 25 extending from its back wall 23.

In this particular exemplification of the invention, there are three individual character elements 21 shown as initial letters S, R, H. The character elements are constructed from sheet metal. Metal of about one-sixteenth inch in thickness is preferably employed for the character elements. Each of the character elements 21 has a lower portion 26 adapted to slidably fit in the longitudinal slot 24 of the tubular member 20, and said lower portion being provided, on its front face, with a longitudinal groove 27 to fit around the edge portion of the curved wall 22 bordering the longitudinal slot 24. The lower portion 26 of each of the character elements has, at each end, a lug extension 28 extending laterally and forwardly therefrom at substantially a right angle thereto, said lugs at the portion thereof of adjoining said lower portion being rounded or curved as shown. The lug extensions 28 are substantially semi-circular shaped and of a size to slidably fit within the tubular member 20, and when engaged therewith, act to firmly hold the character elements 21 on the tubular member in upright position relatively thereto.

The initial letters or other character elements 21, selected as desired to suit the purchaser, are mounted on the tubular member 20 by inserting the lug extensions 28 thereof into the same from either end thereof, after which the tabs 25 are folded inwardly to close the ends of the tubular member, the parts being so proportioned that when all of the initial letters 21 have been mounted on the tubular member, the closure tabs 25 will bear against the outermost of the lug extensions 28 of the character elements at either end of the tubular member so that the character elements are securely held in position thereon. As will be understood, the character elements may be removed by bending back one of the closure tabs 25.

The modified form of character element and tubular character holder member, shown in Fig. 10, is the same as that hereinbefore described and illustrated in Fig. 5 except that the longitudinal slot in the upper side of the curved front wall 22 of the tubular member is not located directly adjoining the back wall 23 but slightly forwardly thereof and the character elements are each provided with a longitudinal groove in each side face thereof to fit around the edge portions of the curved wall 22 at opposite sides of the longitudinal slot therein. In Fig. 10, 29 designates the curved front wall of the tubular member and 30 is the back wall thereof. 31 is the character element provided with a groove 32 in each side face of its lower portion 33. 34 designates the retaining lug at one end of the lower portion 33.

It will be noted that, by the particular construction and arrangement of parts hereinbefore set forth, a necktie clasp of simple, efficient, inexpensive construction is provided that has a tubular front portion providing for the ready selective association and holding of initial letters or the like thereon to present a pleasing ornamental appearance. The tubular character holder front portion is provided in a simple way, the same being economically made of relatively light metal tubing, easily secured on the front bar of

the clasp, the latter reinforcing the relatively light tubular character holder member and providing a firm connection of the same with the rear clamping member so that a strong, satisfactory, and at the same time ornamental construction is afforded that can be produced at low cost, the front bar of the clasp structure being concealed from view from the front by the character holder member.

Referring to the modified form of the device illustrated in Figs. 11 to 16, this, like the construction hereinbefore described and illustrated in Figs. 1 to 10, comprises a front bar having a reverting end portion on the end of which is pivotally mounted a rear spring-pressed clamping member, and a tubular character holding member being secured on the front bar. In Figs. 11 to 16, 35 designates the front bar having the reverting end portion 36 on the outer end of which is pivotally mounted the rear spring-pressed clamping member 37. In this modified form of the device, the tubular character holder member designated 38 is round in cross section, the same being of substantially the same length and width as the front bar 35 and suitably secured on the front side thereof. 39 designates the longitudinal slot in the upper side of the tubular member 38, and 40 are the character elements adapted to slidably fit into the longitudinal slot 39 of the tubular member and each having at its lower end an elongated portion 41 which is circular in cross section and of a size to fit within the tubular member and hold the character elements thereon.

At the ends of the tubular member 38 are closure plugs, each having a reduced portion 42 fitting into one end of the tubular member 38 and having an elongated head 43 extending outwardly therefrom, said head being of the same cross sectional size and shape as the tubular member and forming a continuation thereof. The reduced portion 42 of the closure plug at one end of the tubular member 38 is fixedly secured in any suitable way therein. The other closure plug detachably fits on the other end of the tubular member, the reduced portion 42 of said closure plug being threaded to engage the interiorly threaded portion 44 on this end of the tubular member.

This application contains similar subject matter to that disclosed in copending applications Serial Nos. 73,191 and 73,192. Subject matter shown in this case but not claimed is claimed in copending application 73,191. The present application 73,193 differs from the other cases referred to by the particular means disclosed therein for connecting the tubular front portion of the clasp to the rear clamping member, and also in the particular means for locking the character elements in engagement with the tubular front portion.

What I claim is:

A necktie clasp including an elongated flat front bar to fit over the front of a necktie, a rear clamping member connected with the front bar, a longitudinally extending tubular member on the front side of the front bar of substantially the same length and width as the front bar and substantially concealing the same from view at the front side thereof, said tubular member having a flat back wall fitting against and secured to the front face of said front bar, and said tubular member being provided in its upper side with a longitudinal slot extending throughout the length thereof, a plurality of character elements of

general plate-like form to slidably fit in the longitudinal slot of the tubular front member and each having means at its lower end to slidably fit within the tubular front member adapted to be inserted therein from one end thereof and to hold the character elements thereon standing out from the upper side thereof, said tubular front member having tab extensions at either end thereof extending from its back wall adapted to be bent inwardly to close the ends of the tubular front member and secure the character elements thereon.

IRVING F. CHICHESTER.
